APPARATUS FOR PRODUCING METAL BODIES

Robert K. Hopkins, New York, N. Y., assignor to
 The M. W. Kellogg Company, New York, N. Y.,
 a corporation of Delaware

Application July 22, 1942, Serial No 451,879

15 Claims. (Cl. 22—90)

The invention relates to the production of metal bodies and particularly to the production of consistently uniform semi-finished alloy bodies from raw materials in a single continuous operation in which the necessary heat is supplied by the discharge of electric current through a gap, or gaps, submerged beneath a blanket of protective flux. For a disclosure of this type of operation reference may be had to my prior Patent No. 2,191,479, of February 9, 1940.

The major portion of the cost of the apparatus used commercially for the production of metal bodies by the method exemplified in my prior patent, above identified, is represented by the apparatus elements that supply the raw materials to the electric current discharge, supply the electric current, control the electric current, etc., while the mold elements represent only a minor portion of the cost. Yet since the deposited metal must be cooled sufficiently to permit removal from the mold, the deposited metal must be removed from the mold and the mold prepared for the next deposition, it is the mold element primarily that determines the portion of the work day that the apparatus is not producing metal. Obviously, the cost of the final product is materially effected by the mold element and its arrangement.

The cost of the final product is also materially effected by the character of the metal produced in the mold element. Piping and similar shrinkage defects since they decrease the sound metal yield obviously increase the cost of the final product. Since operations for preventing pipes and other shrinkage defects must be carried out in the mold, the mold elements must be such and so arranged that these operations do not increase the idle time of the metal producing elements of the apparatus.

In cases wherein the metal body removed from the mold is converted into a final product by working operations such as rolling, etc., the proportion of metal rendered defective in the working operations is reflected in the cost of the final product. Substantial metal losses are not uncommon when ferrous alloys are rolled, due to the splitting of the ends of the metal body along the line of roll and the excessive deformation, or fish-tailing, of the ends of the metal body. These losses are sometimes so excessive, as for instance when tool steel ingots are rolled, that it is often necessary to forge the ingots to an intermediate product before rolling. It is, therefore, of utmost importance that the metal body as removed from the mold be in such form and condition that it

may be rolled or otherwise worked with minimum loss.

It is the primary object of this invention to provide a novel apparatus for manufacturing consistently uniform semi-finished alloy bodies from raw materials by the discharge of electric current through a gap submerged beneath a blanket of protective flux, in which, the operation is carried out in such a manner and the apparatus is so constructed and arranged that the portion of the work-day during which the apparatus is not producing metal is reduced to a minimum, the sound metal yield is a maximum and the alloy body produced is in such form and condition that it can be subjected to working operations with a minimum loss of metal.

It is also an important object of this invention to provide a mold arrangement of novel and simple construction in which molten metal may be deposited and solidified, operations for preventing shrinkage defects conducted, and from which the solidified metal body may be removed in a simple and efficient manner and with a minimum idle time of the apparatus used for depositing the molten metal.

It is also a primary object of this invention to provide a novel mold arrangement whose mold cavity defining wall is cooled by the circulation of a heat exchange medium in contact therewith, the mold body being split vertically and the halves being supported for quick and easy movement into and out of mold forming position.

It is a further primary object of this invention to provide a novel mold top element whose mold cavity defining wall is cooled by circulation of a heat exchange medium in contact therewith, the mold top being vertically split and being supported so that its halves may quickly and easily be moved into the open position wherein they do not obstruct access to the mold space and into the closed position wherein they become a continuation of the mold.

It is also an object of the invention to provide a novel ingot of cast metal, and a novel method for its manufacture, which is entirely free from pipe and other shrinkage defects, which in grain size and crystal structure is comparable to cast metal of the same analysis that has undergone working operations or prolonged heat treatment for reducing the grain size, or both, and both of the ends of which are so shaped that they are subject to a minimum of longitudinal splitting or fish-tailing during working operations.

The further objects and advantages of the invention will be apparent from a consideration of

the following detailed disclosure of the invention, taken with the accompanying drawings, in which,

Fig. 1 is a front view of an apparatus embodying the invention,

Fig. 2 is a front view, partly in section, of the mold arrangement,

Fig. 3 is a side view of the mold arrangement,

Fig. 4 is a fragmentary sectional view taken on line 4—4 of Fig. 2,

Fig. 5 is a fragmentary plan view, on an enlarged scale, of a portion of the apparatus,

Fig. 6 is an end view of the apparatus of Fig. 5, and

Fig. 7 is a fragmentary side view of the novel ingot of the invention.

The invention is of general application and may be successfully employed in the production of semi-finished metal bodies of both ferrous and non-ferrous metals and alloys. The invention probably finds its greatest use in the production of semi-finished bodies of ferrous alloys, especially those alloys that contain comparatively large proportions of alloying elements such as chromium, nickel, manganese, vanadium, tungsten, molybdenum, silicon, columbium, aluminum and the like, alone or in combination. Metal bodies of the corrosion resistant alloys and the alloy tool steels are especially suited for production by the method and apparatus of the invention.

The molten metal of the predetermined analysis required for the desired semi-finished alloy body is produced by subjecting raw materials containing the constituents of the alloy to the action of electric current discharged through a gap maintained beneath a protective depth of flux, or slag, which serves to protect the operation from the atmosphere and to remove impurities from, or add desired materials to, the molten metal. The raw materials are supplied to the electric current discharge in independently controlled streams at rates adjusted to constantly supply the constituents in the proportions required to produce the desired analysis. The raw materials are converted into the desired alloy substantially as supplied. A raw material, containing one or more of the constituents, is formed into and supplied as a hollow electrode which becomes a terminus for the gap through which the electric current is discharged. Some or all of the remainder of the raw materials may be supplied in particle form to the gap through the hollow electrode; some of the raw materials may also be supplied in continuous solid form, as a wire or a bar, separately from the hollow electrode, electric current may also be discharged from the ends of the raw materials supplied in the continuous solid form; some of the material may also be supplied through the flux.

The operation is carried out in a mold that is provided with controllable cooling means. The heat input, the quantity of materials fused, and the heat removed through the mold are controlled as required to produce an alloy body of uniform desired analysis and uniform desired characteristics. The conditions just mentioned are so controlled that the flux blanket is maintained at the required degree of superheat, the body of superheated molten metal is maintained large enough to assure proper refining and thorough intermingling of the molten metal, and the molten metal is solidified progressively during the metal producing operation.

This metal producing operation is described in detail in my prior Patent No. 2,191,479 and is employed in performing my present invention.

In operating in accordance with my present invention the molten metal of desired analysis is produced in a novel mold arrangement. The apparatus includes two, or more, of the novel mold arrangements which may be fixed in position, in such case the portion of the apparatus that supplies the raw materials, etc., is movable from one to the other of the mold arrangements, or the mold arrangements may be movable and the portion of the apparatus that supplies the raw materials, etc., fixed in position. The novel apparatus also includes a non-consumable finishing electrode positioned to be easily inserted into the mold space after the metal producing operation is completed. A non-consumable electrode may, if desired, be provided for each mold arrangement.

The novel mold arrangement includes a mold bottom element, a mold body element and a mold top element. The mold space defining walls of these elements are made of a metal of high heat conductivity and are provided with jackets for the circulation of a cooling medium. When metal bodies of high melting point metal, as the iron alloys, are produced copper, brass, bronze, and the like, are preferred for the mold cavity defining walls; water is usually the preferred cooling medium. The mold top and mold body elements are split in a vertical plane and so supported that they may be quickly and easily brought into mold forming position on top of the mold bottom element and may quickly and easily be opened for removal of the metal body produced.

The mold bottom element includes a depression which forms the bottom of the mold cavity. This depression is of diminishing area in the direction of its bottom, at present an approximately hemispherical depression is preferred although conical and similar shapes may be used. The depression is shaped as stated so that the bottom end of the metal body produced can undergo working between rolls with a minimum of fish-tailing and splitting; also, in a depression so shaped the molten metal level rises quickly at the beginning of the operation and protects the wall of the depression from direct exposure to the electric current discharge.

The portion of the mold cavity in the top mold element approximates a bottle neck, or an hour-glass, in shape so that the finishing operation may easily be carried out and the top end of the metal body may be of a shape to undergo working between rolls, or the like, without substantial cracking or fish-tailing.

The apparatus employed includes the apparatus elements for producing molten metal shown and described in my prior Patent No. 2,191,479. These elements and their operation and control will not therefore be gone into in detail here.

The apparatus includes a support 10 upon which is mounted a truck 11 for movement thereon. A bridge 12 is carried on truck 11 and it in turn mounts a truck 13 for movement thereon. Truck 13 carries a vertical frame 14 fixed thereto. A frame 15 is mounted for vertical movement relative to frame 14. Frame 15 carries electrode forming and feeding means 16 which forms strip 17 into hollow electrode 18 and feeds it into the mold. Mechanism 16 is driven by a variable speed motor which may be arc controlled, as is common in the electric furnace art, to form and feed electrode 18 as required to maintain an electric current discharge from its end of constant characteristics; alternately the motor may be run at a constant selected speed and the current

of the discharge adjusted to fuse the electrode at the rate fed. Electrode 18 passes through a contact device 19 which is connected to one side of the electric current supply through cable 20. The other side of the electric current supply is connected by the cable 21 to the mold for convenience the electric current supply will be considered as carried by frame 15. In practice the electric current supply will usually be at a remote point and contact device 19 and mold 27 connected directly to it by cables 20 and 21 respectively. Device 19 is small enough in size and its supports are long enough to permit it to enter the mold space as required to properly guide electrode 18.

Frame 15 carries a plurality of metering devices in housing 22. The metering devices are arranged to receive granular raw materials from hoppers, such as hoppers 23, 24 and 25, and feed them at constant but adjustable rates to tube 26 that leads into hollow electrode 18. The granular materials are thus led by electrode 18 into mold 27 wherein the metal producing operation takes place. A mold arrangement 28 having a mold 27' is shown adjacent mold arrangement 28. These mold arrangements are identical.

Mold arrangement 28, as best shown in Figs. 2 to 6, includes a pair of vertical supports 29 that are united as by welding, to frame members 30. Members 30 may form part of a fixed support, in which case truck 11 is moved as required to align electrode 18 with first one mold and then the other, or members 30 may form part of a movable support, in which case electrode 18 is kept in fixed position and the molds are moved into alignment with it.

Adjacent each end of each support 29 is bolted, or otherwise mounted, an angle piece 31. Each angle piece 31 is provided with a pair of parallel slots 32, see Figs. 5 and 6, through which pass bolts 33. Bolts 33 also pass through a slot 34 in bar 35. Each bar 35 extends from one angle piece 31 on one support 29 to the corresponding angle piece on the other support 29. Blocks 36 are positioned beneath the ends of bars 35. Blocks 36 have tapped holes therein into which bolts 33 are screwed for fixing bars 35 relative to angle pieces 31. Each block 36 is also provided with a threaded hole in which screws stud 37. A pin 38 fixes stud 37 in position in block 36. Stud 37 extends through a hole in support 29, nuts are provided on stud 37 on each side of support 29. At the ends of bars 35 are small blocks 39 having tapped holes through which pass adjustment screws 40 whose ends are adapted to bear against the sides of angle pieces 31. A nut is provided for locking each screw in position. By means of studs 37, and the nuts thereon, and screws 40, and the nuts thereon, the position of bars 35 may be adjusted relative to supports 29. Bolts 33 serve to lock bars 35 in their positions of adjustment. Since, as will be apparent hereinafter, the body and top elements of mold 27 are movable with bars 35, the adjustment means just described, serve for accurately aligning the axis of these mold elements with electrode 18.

Adjacent the bottom ends of members 29 are attached, as by welding, angle members 42 upon which is supported a plate 43, having a central hole therein. Mold bottom element 44 is positioned on plate 43 and is bolted to member 42 by bolts that also pass through plate 43. The bolt holes in plate 43 and mold bottom element 44 are preferably slotted to allow for adjustment of the position of mold bottom element 75

44. Angular adjustment may be secured by placing shims beneath the mold bottom element.

The top wall of element 44 is preferably made of a metal of high heat conductivity such as copper, bronze, brass, etc., and includes a central depression which forms the bottom of the mold cavity. The depression is preferably hemispherical in shape, although shapes approximating a cone and similar shapes of diminishing cross-section may also be used. The bottom wall of element 44 has a central tapped hole through which extends water, or other heat exchange medium, inlet pipe 45. The top end of pipe 45 is preferably notched, or otherwise castellated, and bears against the bottom of the hemispherical depression. The bottom wall of element 44 also includes a baffle 46, shaped to approximate the depression in the top wall, which assures contact of the heat exchange medium with all of the surface of the depression. A plurality of spaced tapped holes are provided in the bottom wall to receive outlet pipes 47 which may be manifolded to lead the heat exchange medium to a place of disposal or of preparation for further circulation. A small bleed line extends through the outer wall of mold bottom element 44 to evacuate any air that may tend to collect in the top of the heat exchange circulation space and to indicate the flow of heat exchange medium through said space.

Bars 48 pass through holes in bars 35 which serve as bearings in which bars 48 may be rotated. The bearing surface is increased as by bushings 49. Bars 48 also pass through holes in the ends of spaced pairs of links 50. The links of each pair are united as by small metal blocks welded or screwed thereto. Bars 48 also pass through holes in flat bars 51; flat bars 51 are fixed to bars 48 as by set screws 52. Vertical pieces 53 are joined, as by welding, to bars 51 to form a frame swingable with bars 48 about the holes in bars 35. To the top and bottom bars 51 are bolted ears 54 which extend from the halves of the body portion 55 of the mold.

Body portion 55 is formed of two halves which when in the closed position, as shown, meet in a vertical plane to form an elongated cylindrical mold space. Each of the halves of body portion 55 includes a semi-cylindrical inner wall 56 of a metal of high heat conductivity such as copper, brass, bronze, etc., and a wall 57 spaced therefrom to form a jacket through which the heat exchange medium is circulated. Ears 54 extend from wall 57; two ears are shown but a greater number may be used. Each end of each half of the body portion is enlarged to form halves of a flange. The bottom walls of the halves include a recess into which fits the top flange of bottom portion 44; by this arrangement easy and accurate alignment of the portions and a metal tight joint between them can be quickly secured. The jacket is enlarged at the flanges and a baffle 58 is provided to assure the heat exchange medium reaching the very end of the surface of wall 57.

Each half of the flange is provided with tapped holes, two are shown, which receive metal bends 59. The bottom bends 59 form the heat exchange medium outlets while the top bends 59 form the heat exchange medium inlets. The heat exchange medium flows from bottom bends 59 through flexible tubing 60 to a manifold to which pipe 45, the heat exchange medium inlet to mold bottom element 44, is connected. The top bends 59 are connected through flexible tubing 60 to the outlet bends 59 of mold top element 61. Small bleed

lines extend through the upper enlargement of the outer walls of each of the halves of body portion 55 to evacuate any air that may collect in the top of the jackets and to indicate the flow of heat exchange medium therethrough.

Mold top 61 is also made up of a pair of halves; these halves when in the closed position meet in the same vertical plane as the halves of body portion 55. The inner wall 62 of each of the halves is made of a metal of high heat conductivity such as copper, brass, bronze, etc.; this wall is so shaped that when the halves are in the closed position the mold space defined approximates an hour-glass or bottleneck in shape. The outer wall 63 is spaced from wall 62 to provide a jacket for the circulation of the heat exchange medium. A pair of bosses, spaced from each other, are found at the top and at the bottom of each of the halves. These bosses have tapped holes which receive metal bends 59. The front four bends 59 are connected by flexible tubing 60 to the heat exchange medium supply and are the heat exchange medium inlets; the four back bends 59 are the heat exchange medium outlets and are connected by flexible tubing 60 to the top bends 59, the inlets, of the body portion 44. Each of the halves is provided with a small bleed line so that air may be evacuated and the flow of the heat exchange medium may be observed.

Each of the halves has an opening in wall 63. Each opening is closed by a plate 64 to which is attached a bar 65. Bars 65 have holes at one end through which pass bars 48. A pair of links 50 straddle bars 65. A set-collar 66 is provided on each bar 48 below the bottom link 50 so that bars 65, and the halves of top portion 61 may be raised by raising bars 48. The weight of the halves of body portion 61 will cause bars 65 to follow the downward movement of bars 48.

To each support 29 is bolted a bracket 66 which carries a forked bearing piece for the fulcrum pin of a bell-crank 67. Each bell-crank 67 has a free end to which is preferably attached a handle, not shown, for actuating the crank. The other end of each bell-crank is forked and carries a pin upon which long links 68 and short link 69 are pivoted. Long links 68 unite cranks 67; a link 48 is positioned on each side of bars 48. The other ends of links 68 are pivoted on pins carried at the ends of long links 70. A link 70 is positioned at each side of bars 48. Links 70 are united, as by welding, to spaced plates 72 which carry washers or bushings 73. Bars 48 pass through enlarged holes in washers 73 and plates 72. The bottom link 50 of the pair of links 50 above links 70 rests on washers 73 so that the weight of bars 48 and all carried by them rests on links 70 when body portion 55 is raised off bottom portion 44.

Body portion 55 is raised and lowered by the manipulation of cranks 67. To lower body portion 55 onto bottom portion 44 so that the mold may be made ready for the metal casting operation, cranks 67 are moved to the dotted line position. This movement is affected by moving either, or both, of the cranks as links 68 cause them to move in unison. As cranks 67 move links 69 rotate to the left thus moving links 70 downwardly as these links are restrained against substantial longitudinal movement by bars 48. To raise body portion 55 off bottom portion 44 the cranks are moved from the dotted to the solid line position. It is to be noted that in the solid line position the pivot pins are not aligned and the cranks are moved off the neutral position

until the free end of the right hand crank touches the stop on its support bracket 66; by this arrangement unwanted movement to the down position is made impossible.

5 In preparing for the metal producing operation mold arrangement 28 is positioned beneath electrode 18, by moving truck 11, when the mold arrangement is immovable, or by moving the mold arrangement when the electrode is immovable. The halves of body portion 55 are brought to the closed position by swinging bars 61 and are fixed in position by passing rods 74 through holes in vertical pieces 53 and tightening the nuts on their ends. Body portion 55 is dropped into position on bottom mold element 44 by moving bell-cranks 67 to, or towards, the dotted line position. The halves of mold top element 61 are separated sufficiently to allow contact device 19 to enter the mold space in the body portion. The alignment of the electrode 18 and the mold cavity is checked and if it is not correct bars 35 are moved as required to produce the desired alignment.

The metal producing elements of the apparatus having been set and adjusted as required to produce the metal of desired analysis; as set forth at length in my prior Patent No. 2,191,479, a quantity of the raw materials, in sub-divided form and in the proportions required to produce the desired metal, is placed in the depression in bottom element 44. The quantity of raw materials should be such that it will be completely fused in the initial stages of the operation and will quickly provide a depth of molten metal sufficient to protect the wall of the depression from direct contact with the electric current discharge. An arc starter, such as a wad of steel wool, is placed in the end of the electrode and frame 15 lowered to enter contact device 19 the proper distance into the mold cavity. The electrode is fed until the arc starter is in contact with the subdivided raw materials. A proper quantity of flux, or slag, is then placed in the mold. The heat exchange inlet is opened to start the circulation through the jackets; it is to be noted that since the heat exchange medium flows from the top element down through the body element and then through the bottom element a counter current flow is established and the coldest heat exchange medium will contact the hottest portion of the mold. The various electric circuits are then closed and the operation begun.

55 The initial surge of current destroys the arc starter to establish a gap between the end of the electrode and the subdivided raw materials, these rapidly fuse to provide a pool of molten metal of sufficient depth to protect the wall of the depression. The fusion of the electrode and the raw materials supplied through it to the heat of the discharge causes the level of the molten metal to rise in the mold cavity. By proper control of the operation conditions the metal produced is solidified progressively, and the flux and a sufficient depth of molten metal are maintained at the necessary temperatures to assure production of homogeneous, highly refined, clean metal of fine grain, and high quality. As the molten flux approaches the top of body portion 55, and contact device 19 is above top element 61, the halves of top element 61 are brought together by movement of bars 65. The halves are kept in this position as by passing rod 75 through bars 65 and tightening the nuts carried by rod 75. When the 75 level of the molten flux has risen to the level in

the bottleneck cavity that is required by the metal body being produced the metal producing operation is stopped; the circulation of the heat exchange medium is continued. The metal producing apparatus is then moved to mold arrangement 28, or if the metal producing apparatus is fixed in position, mold arrangement 28 is moved away and mold arrangement 28' moved beneath the electrode and the operation begun in mold 27.

After electrode 18 has been removed from the mold cavity of mold arrangement 28 indestructible electrode 76 is moved into this mold cavity. Electrode 76 is supported so that it can be quickly positioned in the mold cavity. For example, electrode 76 is shown as clamped on an arm hinged on support 77 so that it can be swung from one to the other of the mold cavities and can be raised or lowered as required; if the mold arrangements are movable the arm supporting electrode 76 may be fixed or one such electrode provided for each mold arrangement. Electrode 76 includes a hollow body portion to which is connected, as by a screw joint, a discharge tip made of copper or other metal of high heat conductivity. A valved line leads heat exchange medium to the upper end of the body portion, a tube within the body portion forms a continuation of the inlet line and terminates a short distance from the tip so that the heat exchange medium is jetted against the tip. The heat exchange medium is removed through an outlet line at the upper end of the body portion. D. C. current is preferably employed, the negative side being connected by cable 20' to the body portion of electrode 76 and the positive side being connected directly by cable 21' or through the ground to mold bottom 44. It is to be noted here that while the ground connection is shown as made to bottom 44 only, in actual practice each half of body portion 55 and top portion 61 are also connected to the ground. With the polarity stated and with proper circulation of the heat exchange medium no appreciable wear of the electrode tip is noticed even after long use.

Electric current is discharged through a gap between the tip of electrode 76 and the surface of the molten metal in mold arrangement 28 to supply heat but not metal while the circulation of the heat exchange medium is continued. The heat is supplied at such a rate that while the solidification of the molten metal goes forward a pool of molten metal of constantly diminishing size is maintained until solidification is complete so that pipes and other shrinkage defects cannot develop. When solidification is complete electrode 76 is removed and the cooling continued until the flux has solidified.

Rods 74 and 75 are then removed and the halves of the mold elements opened and metal body 78 removed. The mold elements may then easily be cleaned after which they are again closed and ready for the next metal body producing operation.

Metal body 78 is made up of a body portion, shown as of substantially constant cross-section but which may have any of the cross-sections usual with ingots, and ends of diminishing cross-section, the bottom end approximates a hemisphere while the top end approximates a spherical segment. By reason of the diminishing cross-section of the ends of the metal body it may be rolled or otherwise work deformed without spreading, or fish-tailing the metal at the ends. Thus, the longitudinal cracks which fre-

quently develop in the ends of a metal body undergoing working are eliminated. The surface of body 78 is free from defects and is of such high quality that grinding or other preparation prior to rolling or other work deformation is unnecessary. The sectioning of a large number of metal bodies 78 of various analyses and the examination of worked products produced from others failed to show evidence of the existence of pipes or other subsurface shrinkage defects. Chemical analysis of samples taken from different locations of the same body seldom show any substantial differences and attest the homogeneity of the metal of the body. Microscopic and macrographic examinations further substantiate this and reveal the fine-grain structure of the body. In general, the grain structure of body 78, as removed from the mold, is as fine as cast metal of the same composition that has undergone prolonged heat treatment for refining the grain size or has been subjected to considerable working. The fineness of grain and the superior qualities of the metal of body 78 are further evidenced by the ease with which it can be rolled deformed and the extremely small metal losses that result. Analyses that are considered delicate and difficult to roll when cast in the conventional way can be rolled without special treatment when produced by the present invention. Thus, high speed tool steels, which when produced in the conventional way must be handled gingerly and always require cogging before rolling, can be rolled directly when produced by the present invention.

I claim:

1. A mold arrangement including a mold body element and a mold top element, said body element being made up of complementary halves adapted to meet in a vertical plane to form the body portion of the mold cavity, each of said halves having an inner wall, an outer wall spaced from said inner wall, and means uniting said walls and enclosing the space between them to provide a jacket for the circulation of a heat exchange medium, said top element being positioned on said body element and being made up of complementary halves adapted to meet in said vertical plane to form the top portion of the mold cavity, each of said halves of said top element having an inner wall, an outer wall spaced from said inner wall and means uniting said walls and enclosing the space between them to provide a jacket for the circulation of the heat exchange medium, said inner walls of the halves of said top element being so shaped that the top portion of the mold cavity approximates an hour-glass in shape, means supporting the halves of said body element and the halves of said top element for movement into and out of mold cavity forming position, said halves of said top element being independently movable, and means for locking said halves in mold forming position.

2. A mold arrangement including a mold body element, a mold top element, and a mold bottom element, said body element being made up of complementary halves adapted to meet in a vertical plane to form the body portion of the mold cavity, each of said halves having an inner wall, an outer wall spaced from said inner wall, and means uniting said walls and enclosing the space between them to provide a jacket for the circulation of a heat exchange medium, said top element being positioned on said body element

and being made up of complementary halves adapted to meet in said vertical plane to form the top portion of the mold cavity, each of said halves of said top element having an inner wall, an outer wall spaced from said inner wall and means uniting said walls and enclosing the space between them to provide a jacket for circulation of the heat exchange medium, said inner walls of the halves of said top element being shaped to form the top portion of the mold cavity into a shape approximating that of an hour-glass, said mold bottom element being made up of a mold cavity defining wall and a wall spaced therefrom to provide a jacket for circulation of the heat exchange medium, means supporting said mold elements, said supporting means including means for moving the halves of said body element and the halves of said top element into and out of mold cavity forming position, the halves of said top element being independently movable, and means for raising and lowering said body element and said top element as a unit off and on said bottom element.

3. A mold arrangement including a mold body element formed of complementary halves adapted to meet in a vertical plane to form the body portion of the mold cavity, a pair of spaced support members, means mounting each of said support members for swinging movement about a substantially vertical line, the lines about which said support members are adapted to swing being parallel, one of said halves being supported by one of said support members for movement therewith and the other of said halves being supported by the other of said support members for movement therewith whereby said halves may be swung into and out of mold cavity forming position, means for locking said support members together to maintain said halves in mold cavity forming position, and means for moving said mounting means to alter the position and the inclination of the lines about which said support members are adapted to swing.

4. A mold arrangement including a mold body element formed of complementary halves adapted to meet in a vertical plane to form the body portion of the mold cavity, a mold bottom element adapted to close the bottom of the mold cavity, a pair of spaced support members, means mounting each of said support members for swinging movement about a substantially vertical line, the lines about which said support members are adapted to swing being parallel, one of said halves being supported by one of said support members for movement therewith and the other of said halves being supported by the other of said support members for movement therewith whereby said halves may be swung into and out of mold cavity forming position, means supporting said mold bottom element beneath the mold cavity forming position of said halves, and means for lowering and raising said support members as a unit to position said mold body element on said mold bottom element and to raise mold body element off said mold bottom element.

5. A mold arrangement including a mold body element formed of complementary halves adapted to meet in a vertical plane to form the body portion of the mold cavity, a mold bottom element adapted to close the bottom of the mold cavity, a pair of spaced support members, means mounting each of said support members for swinging movement about a substantially vertical line, the lines about which said support members are

adapted to swing being parallel, one of said halves being supported by one of said support members for movement therewith and the other of said halves being supported by the other of said support members for movement therewith whereby said halves may be swung into and out of mold cavity forming position, means supporting said mold bottom element beneath the mold cavity forming position of said halves, means for lowering and raising said support members as a unit to position said mold body element on said mold bottom element and to raise said mold body element off said mold bottom element, and means for moving said mounting means to alter the position and the inclination of the lines about which said members are adapted to swing as a unit.

6. A mold arrangement including a mold body element formed of complementary halves adapted to meet in a vertical plane to form the body portion of the mold cavity, a mold top element formed of complementary halves adapted to meet in said vertical plane to form the top portion of said mold cavity, a pair of spaced support members, means mounting each of said support members for swinging movement about a substantially vertical line, the lines about which said support members are adapted to swing being parallel, one of the halves of said mold body element being supported by one of said support members for movement therewith and the other of the halves of said mold body element being supported by the other of said support members for movement therewith whereby the halves of said mold body element may be swung into and out of mold cavity forming position, and a support means mounted on each of said support members for swinging movement relative thereto, each of said support means being swingable relative to its support member about said substantially vertical line, one of the halves of said mold top element being supported by one of said support means for movement therewith and the other of the halves of said mold top element being supported by the other of said support means for movement therewith whereby the halves of said mold top element may be swung into and out of mold cavity forming position independently of said mold body element.

7. A mold arrangement including a mold body element formed of complementary halves adapted to meet in a vertical plane to form the body portion of the mold cavity, a mold top element formed of complementary halves adapted to meet in said vertical plane to form the top portion of said mold cavity, a mold bottom element adapted to close the bottom of said mold cavity, a pair of spaced support members, means mounting each of said support members for swinging movement about a substantially vertical line, the lines about which said support members are adapted to swing being parallel, one of the halves of said mold body element being supported by one of said support members for movement therewith and the other of the halves of said mold body element being supported by the other of said support members for movement therewith whereby the halves of said mold body element may be swung into and out of mold cavity forming position, a support means mounted on each of said support members for swinging movement relative thereto, each of said support means being swingable relative to its support member about said substantially vertical line, one of the halves of said mold top element being supported by one of

said support means for movement therewith and the other of the halves of said mold top element being supported by the other of said support means for movement therewith whereby the halves of said mold top element may be swung into and out of mold cavity forming position independently of said mold body element, means supporting said mold bottom element beneath the mold cavity forming position of the halves of said mold body element, and means for lowering and raising said support members as a unit to position said mold body element on said mold bottom element and to raise said mold body element off said mold bottom element.

8. A mold arrangement including a mold body element made up of complementary halves adapted to meet in a vertical plane to form the body portion of the mold cavity, a vertical support, elongated horizontal members carried by said support adjacent the upper and the lower ends thereof, each of said horizontal members having a pair of spaced holes therein, the holes in said horizontal members being vertically aligned, an elongated cylindrical member journaled for rotation in each line of said vertically aligned holes, a frame member carried by each of said cylindrical members for rotary movement therewith, one of the halves of said mold body element being supported by one of said frame members and the other of the halves of said mold body element being supported by the other of said frame members whereby said halves of said mold body element may be swung into and out of mold cavity forming position, means for moving each of said horizontal members in its horizontal plane to adjust the position thereof, and means for locking each of said horizontal members to said vertical support in any position of adjustment.

9. A mold arrangement including a mold body element made up of complementary halves adapted to meet in a vertical plane to form the body portion of the mold cavity, a vertical support, an elongated horizontal member carried by said support adjacent the upper end thereof, a second elongated horizontal member carried by said support adjacent the lower end thereof, said horizontal members each having a pair of spaced holes therethrough, the holes in one of said elongated horizontal members being vertically aligned with the holes in the other of said elongated horizontal members, an elongated cylindrical member journaled for rotation in each line of said vertically aligned holes, a frame member united to each of said cylindrical members and swingably movable therewith, said halves of said mold body element being mounted for movement with said frames whereby said halves of said mold body element may be swung into and out of mold cavity forming position, means at the ends of said elongated horizontal members for moving said elongated horizontal members longitudinally in their respective horizontal planes, means adjacent each end of each of said horizontal members for moving said horizontal members transversely in their respective planes, and releasable means for rigidly uniting said horizontal members to said support.

10. A mold arrangement including a mold body element made up of complementary halves adapted to meet in a vertical plane to form the body portion of the mold cavity, a vertical support, a pair of spaced horizontally aligned members extending from said support adjacent the upper end thereof, a second pair of spaced horizontally aligned members extending from said support adjacent the lower end thereof, an elongated hori-

zontal member spanning each pair of said spaced horizontally aligned members and extending therebeyond, screw means at each end of each of said elongated horizontal members adapted to bear against the adjacent horizontal member whereby by adjustment of said screw means said elongated horizontal members may be moved longitudinally, a block member beneath each of said spaced horizontally aligned members, screw means of adjustable length connected to each of said block members and extending from said support whereby said block members may be moved laterally relative to their respective elongated horizontal members by adjustment of said screw means, means for releasably clamping each end of each of said elongated horizontal members between their respective block members and horizontally aligned members, said elongated horizontal members each having a pair of spaced holes therethrough, the holes in one of said elongated horizontal members being vertically aligned with the holes in the other of said elongated horizontal members, an elongated cylindrical member journaled for rotation in each line of said vertically aligned holes, and a frame member united to each of said cylindrical members and swingably movable therewith, said halves of said mold body element being mounted for movement with said frame members whereby said halves of said mold body element may be swung into and out of mold cavity forming position.

11. A mold arrangement including a mold body element made up of complementary halves adapted to meet in a vertical plane to form the body portion of the mold cavity, a mold top element made up of complementary halves adapted to meet in said vertical plane to form the top portion of the mold cavity, a vertical support, an elongated horizontal member carried by said support adjacent the upper end thereof, a second elongated horizontal member carried by said support adjacent the lower end thereof, said horizontal members each having a pair of spaced holes therethrough, the holes in one of said elongated horizontal members being vertically aligned with the holes in the other of said elongated horizontal members, an elongated cylindrical member journaled for rotation in each line of said vertically aligned holes, a frame member united to each of said cylindrical members and swingably movable therewith, said halves of said mold body element being mounted for movement with said frames whereby said halves of said mold body element may be swung into and out of mold cavity forming position, a support member mounted for rotation adjacent the upper end of each of said elongated cylindrical members, said halves of said mold top element being mounted for movement with said support members whereby said halves of said mold top element may be swung into and out of mold cavity forming position independently of the halves of said mold body element, means at the ends of said elongated horizontal members for moving said elongated horizontal members longitudinally, means adjacent each end of said elongated horizontal members for moving said elongated horizontal members transversely, and releasable means for rigidly uniting said elongated horizontal members to said support.

12. A mold arrangement including a mold body element made up of complementary halves adapted to meet in a vertical plane to form the body portion of the mold cavity, a vertical support,

elongated horizontal members carried by said support adjacent the upper and the lower ends thereof, each of said horizontal members having a pair of spaced holes therein, the holes in said horizontal members being vertically aligned, an elongated cylindrical member journaled for rotation in each line of said vertically aligned holes, a frame member carried by each of said cylindrical members for rotary movement therewith, one of the halves of said mold body element being supported by one of said frame members and the other of the halves of said mold body element being supported by the other of said frame members whereby said halves of said mold body element may be swung into and out of mold cavity forming position, means for moving each of said horizontal members in its horizontal plane to adjust the position therein, means for locking each of said horizontal members to said support in any position of adjustment, and means carried by said support for supporting said elongated cylindrical members.

13. A mold arrangement including a mold body element made up of complementary halves adapted to meet in a vertical plane to form the body portion of the mold cavity, a mold bottom element adapted to close the bottom of said mold body element, a vertical support, elongated horizontal members carried by said support adjacent the upper and the lower ends thereof, each of said horizontal members having a pair of spaced holes therein, the holes in said horizontal members being vertically aligned, an elongated cylindrical member journaled for rotation in each line of said vertically aligned holes, said cylindrical members being vertically movable along said lines of aligned holes, a frame member carried by each of said cylindrical members for movement therewith, one of the halves of said mold body element being supported by one of said frame members and the other of the halves of said mold body element being supported by the other of said frame members whereby said halves of said mold body element may be swung into and out of mold cavity forming position, means for adjusting the position of each of said horizontal members in its horizontal plane to adjust the inclination and position of said cylindrical members, means for locking said horizontal members to said vertical support in any position of adjustment, and means carried by said support for raising and lowering said cylindrical members whereby said mold body element may be raised from and lowered onto said mold bottom element.

14. A mold arrangement including a mold body element made up of complementary halves adapted to meet in a vertical plane to form the body portion of the mold cavity, a mold bottom element adapted to close the bottom of said mold body element, a vertical support, elongated horizontal members carried by said support adjacent the upper and the lower ends thereof, each of said horizontal members having a pair of spaced holes therein, the holes in said horizontal members being vertically aligned, an elongated cylindrical member journaled for rotation in each line of said vertically aligned holes, said cylindrical members being vertically movable along said lines of aligned holes, a frame member united to each of said cylindrical members for movement therewith, the halves of said mold body element being united to said frame members

whereby said halves may be swung into and out of mold cavity forming position, horizontal means extending from said vertical support adapted to carry said mold bottom element, a pair of horizontally aligned support elements extending from said vertical support and straddling said elongated cylindrical members, a bell-crank mounted for movement on each of said support elements, elongated horizontal links means connected to one end of each of said bell-cranks to transmit the movement of one bell-crank to the other, a short link means connected to each of said ends of said bell-cranks, a second elongated horizontal link means connected to said short link means, and means carried by said second elongated horizontal link means adapted to support said frame members and said cylindrical members whereby by movement of said cranks said cylindrical members, said frame members and said mold body element may be raised or lowered to position said mold body element on said bottom element and to raise said mold body element off said mold bottom element.

15. A mold arrangement including a vertical support, elongated horizontal members carried by said vertical support adjacent the upper and the lower ends thereof adjustable relative thereto, each of said elongated horizontal members having a pair of spaced holes therein, the holes in said elongated horizontal members being vertically aligned, an elongated cylindrical member journaled for rotation in each line of said vertically aligned holes, said elongated cylindrical members being vertically movable along said line of aligned holes, a pair of spaced frame members, each of said frame members including horizontal members united to one of said elongated cylindrical members, said horizontal members of one frame being horizontally aligned with said horizontal members of the other frame, link members having holes at their ends through which end cylindrical members pass positioned on each side of each aligned pair of said horizontal members, means uniting the link members of each pair of link members, a pair of horizontally aligned support elements extending from said vertical support and straddling said elongated cylindrical members, a bell-crank mounted for oscillatory movement on each of said support elements, a pair of parallel elongated links through which said elongated cylindrical members are adapted to pass, one end of each of said parallel elongated links being pivoted to one end of one of said bell-cranks, the other end of each of said parallel elongated links being pivoted to the same end of the other of said bell-cranks, a short link pivoted to the end of each of said bell-cranks to which said parallel elongated links are pivoted, a second pair of parallel elongated links through which said elongated cylindrical members are adapted to pass, one end of each links of said second pair of parallel elongated links being pivoted to one of said short links, and means united to said second pair of parallel elongated links having holes therethrough through which said elongated cylindrical members pass whereby when said bell-cranks are actuated said second pair of parallel elongated links are restrained against substantial horizontal movement, said second pair of parallel elongated links serving to carry said elongated cylindrical members and said frame members.

ROBERT K. HOPKINS.
